UNITED STATES PATENT OFFICE

2,037,720

ROAD MACHINE

Carl A. Gustafson, Peoria, Ill., assignor to Caterpillar Tractor Co., San Leandro, Calif., a corporation of California

Original application April 27, 1931, Serial No. 533,179. Divided and this application May 27, 1933, Serial No. 673,194

10 Claims. (Cl. 280—80)

My invention relates to road machines and particularly to graders, this application being a division of my application Serial No. 533,179, filed April 27, 1931, and entitled Road machine.

5 It is an object of the invention to provide an earth-working machine in which the earth-engaging tool is capable of a wide range of adjustments, is flexible in use, and designed to be easily controlled by the operator.

10 Another object of the invention is to provide a road machine having means for positioning an earth-engaging tool to make a high-angle cut including means for tilting the wheels with respect to the frame.

15 Another object of the invention is to provide a road machine having means for positioning an earth-engaging tool to make a high-angle cut including means for adjusting a wheeled support transversely with respect to the road machine frame.

20 Other objects will appear as the description progresses.

Fig. 1 is a plan view of the machine.

Fig. 2 is a side elevation of the rear end on line

25 2—2 of Fig. 1.

Figs. 3 to 5 illustrate the construction of the front end.

Fig. 3 is a front elevation.

Fig. 4 is a right side elevation from line 4—4 of

30 Fig. 3.

Fig. 5 is a vertical longitudinal section on line 5—5 of Fig. 3.

Figs. 6 to 8 illustrate the construction of the rear end.

35 Fig. 6 is a rear elevation from line 6—6 of Fig. 1.

Fig. 7 is a section of a detail on line 7—7 of Fig. 6.

Fig. 8 is a horizontal plan.

Fig. 9 is a transverse vertical section of a portion of the adjusting mechanism on line 9—9 of Figs. 1 and 10.

40 Fig. 10 is a horizontal section of a portion of the adjusting mechanism on line 10—10 of Fig. 9.

Frame (Sheets 1 to 6)

45 The frame of the machine is substantially symmetrical with respect to the longitudinal axis, and includes two side channels 10, 11, which extend substantially the length of the machine and have a slight convergence toward the front end (Fig. 1). These side channels are interconnected by cross members and braces.

At the front end of the machine (Figs. 1, 3 and 4) plate 12 is riveted to the forward ends of side channels 10, 11. Angle 13 at the front edge of

plate 12 is riveted to plate 12 and to side channels 10, 11. Beneath plate 12 is bracket 14 having central horizontal portion 15 provided with boss 16, and having vertically extending portions 17, 18, which are riveted inside the forward ends of side channels 10, 11, respectively. 5

At the rear end of the machine (Figs. 1, 2, 6 and 8), side channels 10, 11 are bent downwardly and rearwardly, and plate 25 is secured to their under sides. Upper edge of plate 25 is reinforced 10 by angle 26. Pairs of angle extensions 27, 28 are secured to the ends of side channels 10, 11, respectively, by brackets 29, 30, respectively, by plates 31, 32, and by straps 33. T-bar 34 has its ends overlapping straps 33, and is secured to the 15 lower edge of plate 25. To the rear ends of extensions 27, 28 is secured angle 35. Vertical posts 36, 37 are secured to the inner sides of side channels 10, 11, respectively, and serve to support a portion of the blade lifting mechanism. Channel 20 38 is secured to the lower ends of posts 36, 37, and in addition to reinforcing the framework serves in conjunction with inverted U-bracket 39 to support platform 40, the forward edge 41 of which extends through aperture 42 in plate 25. A 25 framework, consisting of bar 43 secured to post 37, bars 44, 45 secured to angle 35 and interconnected by strap 46, supports part of the mechanism for tilting the rear wheels.

In the central portion of the machine above 30 the blade (Figs. 1 and 2), the ends of a pair of spaced apart angles 47, 48 are secured to the top faces of side channels 10, 11 and the connections are reinforced by gussets 49, 50 and angles 51, 52. Angles 47, 48 also serve to support part of the 35 blade lifting mechanism. The end of a pair of spaced apart angles 53, 54 are secured to the bottom faces of side channels 10, 11 beneath angles 47, 48; the central web of T-bar 55 is interposed between angles 53, 54 and is secured thereto. 40 Angles 53, 54 and T-bar 55 support the center shift mechanism. The central portion of side channels 10, 11 are further reinforced by angles 56, 57 which are secured to the inner lower edges thereof and extend rearwardly to posts 36, 37 to 45 which they are also secured.

Intermediate the front end and the central cross members (Fig. 1), is cross member 58 which is fabricated, having a substantially I-beam cross 50 section and end flanges for securing it to side channels 10, 11. The connections of cross member 58 with the side channels is reinforced by gussets 61, 62. Cross member 58 also serves as a support for part of the compensating spring 55

mechanism fully disclosed in my above noted application.

To obtain rigidity and to prevent weaving, diagonal braces 63, 64, 65, 66, 67, 68 are employed, 5 as shown in Fig. 1. Cross pieces 69, 70, 71 are connected to side channels 10, 11 to provide supports for adjusting mechanisms.

Front wheels (Sheets 1, 3, 4 and 5) (100 series numerals)

10 Front wheels 100, 101 (Fig. 3) are journaled on spindles which are integral with bell-cranks 102, 103, pivoted at 104, 105, in angles 106 (Fig. 4) which comprise the front axle. Upwardly converging channels 107, 108 are secured at their lower ends to angles 106 and at their upper ends to casting 109, having boss 110 (Fig. 5) apertured at 111 and contacting the under side of boss 16 in the horizontal portion 15 of frame bracket 14. 15 Aperture 111 is defined by a vertically arcuate wall of boss 110 for a purpose later described.

Hollow kingbolt 112 passes freely through aperture 111 and is supported in boss 16 through 20 which it passes, and at 113, 114 in housing 115 which is provided with flange 116 for attachment to plate 12 of the main frame. Nut 112' is threaded to the lower end of kingbolt 112 and is adapted to be locked thereon. Nut 112' on kingbolt 112 is spaced below the bottom of boss 110 to allow 25 oscillation in vertical planes of the front wheel and axle assembly with respect to the main frame. For this purpose also, aperture 111 in boss 110 is of larger diameter than kingbolt 112 and is 30 defined by a vertically arcuate wall. The front axle and wheels also pivot on the vertical axis of the kingbolt.

The front wheels can be tilted with respect to 35 the front axle by rocking bell-cranks 102, 103 (Fig. 3) on their pivots 104, 105. For this purpose the upstanding arms 117, 118 of bell-cranks 102, 103 are pivotally connected to shift bar 119. Movement of shift bar 119 will impart equi-angular oscillations to the bell-cranks. To facilitate 40 operation of shift bar 119, a strap 120 is pivotally connected to axle 106 and lug 121 secured to the shift bar.

To operate shift bar 119, sector 122 is secured 45 thereto and meshes with pinion 123 (Fig. 4) on shaft 124 journaled in housing 125 and provided with worm gear 126 (Fig. 3) which is rotated by worm 127 on shaft 127', also journaled in housing 125. Housing 125 has a portion which extends 50 downwardly to fit between angles 106 to which it is secured by bolts.

Shaft 128 (Fig. 5) passes through hollow king-bolt 112 and is operatively connected to worm 127 by an extensible driving connection comprising 55 square shaft 129 telescopically engaging within hollow square sleeve 130. Sleeve 130 has a universal connection 131 with shaft 128, and shaft 129 has a universal connection 132 with worm shaft 127'. Rotation of shaft 128 effects rotation 60 of worm 127, worm wheel 126, shaft 124, pinion 123, to shift bar 119 to tilt the wheels. The extensible universal connection between shaft 128 and worm 127 enables the shift bar to be operated 65 in all positions of the wheels and axle with respect to the frame.

70 Shaft 128 (Fig. 5) has bevel gear 133 keyed to its upper end and retained thereon. Bevel gear 133 is journaled at 134 in housing 135 which fits the reduced upper end portion of kingbolt 112 and is secured thereto by means of lock bolt 136.

Bevel gear 133 is driven by bevel pinion 137 keyed to shaft 138 which is journaled at 139 in housing 135 and is provided with sleeve 140 received in housing 135 at 141. Shaft 138 is retained in place in housing 135 by means of nut 142 and yoke 143, 5 which is secured to shaft 138 and forms part of universal joint connection 144, the other yoke 145 of which is secured to shaft 146. The rear end of shaft 146 is supported at 147 (Fig. 1) in support 69, where it is connected by universal 10 joint 148 to telescopic shaft 149 which is connected by universal joint 150 to stub shaft 151 (Fig. 10) journaled in housing 152 secured to support 70. Within housing 152, shaft 151 has secured thereto gear 153 which is adapted to be 15 driven by pinion 154 splined on sleeve 155 to which operating crank 156 is secured. Pinion 154 is adapted to be driven by sleeve 155 and to be axially adjusted thereon for a purpose hereinafter described. When pinion 154 is in mesh with gear 153, rotation of crank 156 causes tilting 20 of the front wheels.

Rear wheels (Sheets 1, 2, 5 and 6) (200 series numerals)

25

Rear wheels 200, 201 (Fig. 6) are journaled on spindles integral with bell-cranks 202, 203 pivoted at 204, 205 in brackets 206, 207 (Fig. 8) secured to the ends of I-beam 208. Angles 209, 210 30 are riveted along the lower outside edges of I-beam 208 and are joined at their ends 211, 212, 213, 214, to brackets 206, 207 by welding to provide continuous flanges along the bottom edges of the axle for cooperation with guides 215, 216, 35 217, 218 on main frame extensions 21, 28.

Rear axle 208 is transversely adjustable with respect to the main frame. For this purpose rack 219 (Fig. 7) is secured to the rear face of I-beam 208 and pinion 220 is arranged to mesh therewith. 40 Pinion 220 is operated in unison with worm gear 221. Shaft 222 on which they are secured is journaled in housing 223 which has a depending portion 224 secured to the upstanding web of frame angle 35. Worm gear 221 (Fig. 8) is driven by 45 worm 225. Worm shaft 226 is journaled in housing 223 and is operated by crank 227. Axle 208 can be shifted transversely of the main frame by operation of crank 227.

The rear wheels can be tilted with respect to 50 the rear axle. For this purpose the upstanding arms 228, 229 (Fig. 6) of bell-cranks 202, 203 are interconnected by shift bar 230 which is guided by strap 231 and shifted by pinion 232 (Fig. 2) and sector 233, the latter being secured to bar 55 230. Pinion shaft 234 is journaled in housing 235 within which worm gear 236 (Fig. 6) is secured to the shaft. Worm 237 meshes with worm gear 236 and worm shaft 238 is also journaled in housing 235. Rotation of worm 237 causes bar 60 230 to be shifted to tilt the wheels with respect to the axle.

Worm 237 is operated by crank 239 whose shaft 65 240 is journaled in housing 241 supported on framework 43, 44, 45. Secured to shaft 240 within housing 241 is bevel pinion 242 which drives gear 243, the latter being secured to a short vertical shaft 244, the lower end of which is connected by universal joint 245 to square hollow sleeve 246 within which is received square shaft 247, the lower end of which is connected by universal joint 248 to worm shaft 238. Rotation of 70 crank 239 results in tilting the wheels, and, due to the extensible universal joint connections be- 75

tween shaft 244 and shaft 238, the wheels can be tilted by crank 239 in any position shifted of the wheels and axle.

5 *Blade mounting and adjustment (Sheets 1, 2, 4 and 7)*

Blade 300 (Fig. 1) is mounted on circle 315 by beam 318, being adjustably secured to end portions 319, 320 of said beam. The circle is 10 revolvably mounted in a framework including forwardly converging side bars 342, 343, connected at their rear ends to a suitable cross bar, and connected intermediate their ends by casting 351.

The circle supporting framework is connected 15 by drawbars 359, 360 (Fig. 1) to the front end of the main frame (Fig. 5) where horizontal portion 15 of U-bracket 14 has a rearwardly extending fork 361 secured thereto. Drawbars 359, 360 converge forwardly to a connection to which 20 they are bolted. In the connection is a bolt 363 having an apertured head 364 which is connected by pin 365 in fork 361. Bolt 363 can swing in a horizontal plane about the vertical axis of pin 365, and, due to the rounded edges of the aperture 25 in the head 364 and the wide spacing of the jaws of the fork 361, bolt 363 is capable of a limited oscillation in the vertical plane, as well. The rear ends of the drawbars are pivotally connected to the circle supporting framework as fully 30 disclosed in the above noted application. By reason of these pivotal connections between the drawbars and the circle supporting framework, the framework, together with the circle and the blade, can be raised and lowered with respect to 35 the drawbars, or, in other words, the angle between the drawbars and the plane of the circle can be varied. Also, the drawbars, together with the circle and blade assembly, as a unit, are capable of a limited universal movement about the 40 intersection of the axes of pin 365 and bolt 363 as a center.

To summarize the movements of adjustment of which the circle is capable, they are, an arcuate movement in a horizontal plane about the vertical axis of pin 365; an arcuate movement in vertical planes containing the axis of pin 365; oscillation about the axis of bolt 363; a jack-knife movement between the circle and the drawbars; and oscillation of the circle about its center. 50 The desired circle adjustment is usually obtained by combinations of these movements.

The blade lift includes opposite telescopic links 402, 403 (Figs. 1 and 2) connected to the circle supporting framework and to lift arms 408, 409 45 on shafts 410, 411. Said shafts 410, 411 are operated through suitable worms and worm wheels in housings 418, 419 by operating wheels 424, 425. By manipulation of wheels 424, 425, the operator is enabled to raise or lower either end of the 55 blade.

Means are provided for (1) shifting the center of the circle transversely of the machine or about the center of pin 365; (2) shifting the circle on its own center, and (3) adjusting the plane of 60 the circle with respect to the drawbars.

(1) For shifting the center of the circle, the supporting frame of the circle is adapted to be variously connected by a link to a rack on the main frame which can be slid transversely of the 70 main frame. The circle supporting framework is adapted for connection to a link 502 (Fig. 2) having a hooked end for connection with apertured lug 503, depending from rack 506 which 75 is formed for engagement with the flanges of T-

bar 55, which, as explained before, is secured to the main frame. Rack 506 is adapted to slide along bar 55 and for this purpose is engaged with pinion 509 operated by means in housing 511 (Fig. 1) and shaft 514. The rear end of hollow shaft 514 has handwheel 517 thereon and is supported in bracket 515 which is secured to cross member 71 in the main frame.

(2) For shifting the circle on its center, it is provided with an arcuate rack secured underneath the inwardly extending flange of circle 315. The rack is engaged with a suitable pinion operated by means in housing 524 and suitable shafting.

For adjusting the plane of the circle with respect to the drawbars (Fig. 1) an adjustable connection is provided between drawbars 359, 360 and side bars 342, 343, said connection comprising a nut and screw operated by telescopic shaft 513, connected by universal joint 575 to shaft 20 516. The rear end of shaft 516 (Fig. 10) is connected by universal joint 577 to stub shaft 578 which is journaled in housing 152. Within housing 152 on shaft 578, is secured gear 579 which can be driven by pinion 154 by shifting pinion 154 25 into mesh therewith. This is effected by rotating lever 580 in the direction of the arrow in Fig. 10, lever 580 is pivoted to housing 152 on pin 581, the lower end of which (Fig. 9) has a short crank 582 integral therewith from which 30 depends a pin 583 engaging with grooved collar 584 (Fig. 10) on pinion 154. When pinion 154 is engaged with gear 579, operation of crank 156 adjusts the nut and screw thereby adjusting the circle with respect to the drawbars. Due to the 35 telescopic shaft 513 and the universal joints, this adjustment can be made in any position of the circle or drawbars.

In the foregoing description, a plurality of adjusting mechanisms have been described, each 40 one of which is adapted to effect adjustment of the blade to vary its cutting position. The combined effect of all such adjusting mechanisms is utilized in positioning the blade to make a high angle cut, as fully described in my aforesaid application. These adjusting mechanisms include the means for tilting the wheels as described above, and the means for shifting the rear wheels with respect to the frame of the machine, as in the high angle cutting position of the blade the 50 wheels are tilted and the rear wheels are shifted to a position inside the cutting edge or blade.

I, therefore, claim as my invention:

1. In a road machine, a frame, including two side channels, a plate secured to the rear ends of 55 said channels, angle extensions secured to the rear ends of said channels, a cross piece secured to the rear ends of said extensions, a pair of guides on each of said extensions, an axle comprising an I-beam and angles secured thereto and 60 engaging said guides, brackets secured to the ends of said I-beam and welded to said angles to provide a continuous flange for cooperation with said guides, bell-cranks pivoted in said brackets, a bar connecting the upper arms of said bell-cranks, and wheels journaled on spindles formed on the lower arms of said bell-cranks.

2. In a road machine, a frame, including two side channels, a plate secured to the rear ends 70 of said channels, angle extensions secured to the rear ends of said channels, a cross piece secured to the rear ends of said extensions, a pair of guides on each of said extensions, an axle comprising an I-beam and angles secured thereto and 75 engaging said guides, a rack formed on said

axle, a housing mounted on said cross piece, a shaft journaled in said housing, carrying a worm gear and a pinion meshing with said rack, a second shaft journaled in said housing carrying an operating crank and a worm engaging said worm gear, brackets secured to the ends of said I-beam, bell-crank pivoted in said brackets, a bar connecting the upper arms of said bell-cranks having a rack, wheels journaled on spindles formed on the lower arms of said bell-cranks, a second housing mounted on said axle, a third shaft journaled in said second housing carrying a second worm gear and a second pinion meshing with said rack on said bar, a fourth shaft journaled in said second housing carrying a second worm engaging said second worm gear and having a universal connection with an extensible operating linkage.

3. In a road machine, a frame, an axle mounted thereon for lateral displacement with respect thereto, wheels mounted on said axle for simultaneous tilting movement with respect thereto, tilting means mounted on said axle and secured for lateral movement therewith as a unit, operating means therefor mounted on said frame, and an extensible connection between said operating means and said tilting means.

4. In a road machine, a frame, an axle laterally displaceable with respect thereto, wheels on said axle, means mounted on said axle and secured for movement therewith as a unit for varying the angular relation between said frame and said wheels, operating means therefor mounted on said frame, and extensible means universally connected to said varying means and said operating means.

5. In a road machine, a frame, an axle mounted thereon for lateral displacement with respect thereto, means including a rack and pinion for displacing said axle laterally with respect to said frame, wheels mounted on said axle for simultaneous tilting movement with respect thereto, tilting means including a parallel linkage mounted on said axle, said tilting means being secured for movement as a unit with said axle, operating means therefor mounted on said frame, and an extensible connection between said operating means and said tilting means.

6. In a road machine; a frame; supporting means for said frame shiftable with respect to said frame as a unit and tilttable with respect to said frame comprising an axle mounted on said frame for shifting movement, and spaced ground-engaging members mounted on said axle for said tilting movement; and means for effecting tilting movement of said ground-engaged members in any shifted position of said axle comprising adjusting mechanism secured to said axle for movement therewith as a unit, operating means on said frame, and flexible shafting connecting said operating means and said adjusting mechanism.

7. In a road machine; a frame; supporting means for said frame shiftable with respect to

said frame as a unit and tilttable with respect to said frame comprising an axle mounted on said frame for shifting movement, and spaced ground-engaging members mounted on said axle for said tilting movement; and means for effecting simultaneous tilting movement of said ground-engaging members in any shifted position of said axle comprising adjusting mechanism secured to and shiftable as a unit with said axle, operating means mounted in a relatively fixed position on said frame, and extensible telescopic shafting movably connected at one end thereof to said operating means and at the opposite end thereof to said adjusting mechanism.

8. In a road machine, a frame, rear axle means adjustably connected to said frame for endwise movement with respect thereto, ground-engaging supporting means adjustably mounted on said axle means for movement therewith with respect to said frame, means secured to said axle means and movable therewith as a unit for adjusting said supporting means with respect to said axle means, operating means for said adjusting means, means for supporting said operating means on said frame in an elevated position above said axle means, and extensible shafting movably connected to said operating means and to said adjusting means.

9. In a road machine, a frame, rear axle means adjustably connected to said frame for endwise movement with respect thereto, ground-engaging supporting means adjustably mounted on said axle means for movement therewith with respect to said frame, means secured to said axle means and movable therewith as a unit for adjusting said supporting means with respect to said axle means, operating means for said adjusting means, an operator's station on said frame, means for supporting said operating means on said frame adjacent said operator's station, and extensible shafting movably connected to said operating means and to said adjusting means.

10. In a road machine, a frame, an axle, guide means on said frame connecting said axle thereto for endwise shifting movement, a rack on said axle, means on said frame for shifting said axle with respect to said frame including a gear engaging said rack, opposite bell-cranks pivotally mounted on the ends of said axle and having horizontally and vertically extending arms, ground-engaging wheels journaled on said horizontal arms, a link member pivotally connected adjacent its ends to said vertical arms, an arcuate rack secured to said member and free of any connection with said frame, means secured to and movable as a unit with said axle for tilting said wheels with respect to said frame including a gear engaging said arcuate rack, control means on said frame for said tilting means, and extensible shafting movably connected to said control means and said tilting means for enabling tilting of said wheels in any laterally shifted position of said axle.

CARL A. GUSTAFSON.

CERTIFICATE OF CORRECTION.

Patent No. 2,037,720.

April 21, 1936.

CARL A. GUSTAFSON.

It is hereby certified that error appears in the printed specification of the above numbered patent requiring correction as follows: Page 3, first column, line 2, for "position shifted" read shifted position; and page 4, first column, line 56, claim 6, for "ground-engaged" read ground-engaging; and that the said Letters Patent should be read with these corrections therein that the same may conform to the record of the case in the Patent Office.

Signed and sealed this 14th day July, A. D. 1936.

Henry Van Arsdale
